UNITED STATES PATENT OFFICE

161,571

TAPE MEASURE HOLDER

Leo E. Dauenhauer, Santa Rosa, Calif.

Application July 5, 1950, Serial No. 10,963

Term of patent 14 years

(Cl. D52—2)

To all whom it may concern:

Be it known that I, Leo E. Dauenhauer, a citizen of the United States, residing at Santa Rosa, in the county of Sonoma and State of California, have invented a new, original, and ornamental Design for a Tape Measure Holder, of which the following is a specification, reference being had to the accompanying drawing, forming part thereof.

Figure 1 is a front elevation of the tape measure holder;

Figure 2 is a rear elevation;

Figure 3 is a side elevation;

Figure 4 is a top plan view; and

Figure 5 is an isometric view.

I claim:

The ornamental design for a tape measure holder, as shown.

LEO E. DAUENHAUER.
